(57) **CLAIM**

The ornamental design for transmitter pod for medical ultrasound machine, as shown and described.

DESCRIPTION

FIG. 1 is a perspective view of a transmitter pod for a medical ultrasound machine showing my new design;

FIG. 2 is a right elevation view thereof;

FIG. 3 is a left elevation view thereof;

FIG. 4 is a top plan view thereof;

FIG. 5 is a bottom plan view thereof and the four small holes and the control button illustrated in broken line form no part of the claimed design.

FIG. 6 is a front elevation view thereof;

FIG. 7 is a rear elevation view thereof; and,

FIG. 8 is a perspective view thereof and an environmental structure illustrated in broken line, which does not form part of the design.
